KEYBOARD CONTROLLED TELEGRAPH
APPARATUSAlan Arthur Kirchel, Croydon, England, assignor
to Creed and Company Limited, Croydon, Eng-
land, a British companyApplication April 1, 1949, Serial No. 84,864
In Great Britain April 5, 1948

5 Claims. (Cl. 178—17)

1

This invention relates to keyboard controlled telegraph apparatus in which key levers coact with bars to effect the transmission of code signals to a line circuit or to effect the perforation of a tape for subsequent control of the transmission of such signals.

The layout of many keyboards for this purpose has been made so as to approach as nearly as possible to the standard typewriter keyboard layout, so that commercially trained typists will experience minimum difficulty with telegraph machines. In the standard typewriter keyboards each key in the top row carries two symbols.

In order to adapt such a keyboard to a teleprinter code, in which the two symbols on one key are represented by different code combinations, there was described and claimed in U. S. Patent No. 1,988,943, a keyboard mechanism in which two sets of permutation members were provided for, actuation under control of a single key lever, each set in accordance with a different code combination, and in which means was provided for operatively associating either of said sets of permutation members with further apparatus which it was desired to control. In the embodiment described in the said patent there were provided for a five unit code, two sets of five combination bars so called, both sets being operated by the same key lever, but the operation of a shift key lever, caused one or the other set of combination bars to be operatively associated with the apparatus to be controlled by the keyboard.

It is to be understood that the shift key lever, here referred to, has no relation to a key lever for causing the combination bars to be set in a combination representing the figure shift or letter shift signal used in the teleprinter code, for both symbols on a given key, in the circumstances in question, are sent in the upper case. The shift key lever referred to is akin to the shift key lever in a typewriter and actuation of such key lever performs a mechanical operation in the keyboard.

It is the object of the present invention to provide a keyboard mechanism in which provision is made for two different symbols to be of the same key but in which the action of the keys is as light as possible.

According to the present invention there is provided a keyboard mechanism for telegraph apparatus comprising a set of character key levers, a first set of combination members, in operative relation to said character key levers, a second set of combination members positioned

2

out of operative relation to said character key levers, a shift key lever, means operative upon the actuation of said shift key lever for placing the second set of combination members in and removing the first set of combination members out of operative relation to said character key levers.

It will be clear that since only one set of combination members is actuated by a key lever at any one time, the touch of the keyboard is made lighter than in the embodiment described in the above mentioned patent.

The invention will be better understood from the following description of one embodiment thereof taken in conjunction with the drawings, in which:

Fig. 1 is a view in elevation of a combination bar of the keyboard mechanism, showing the mechanism for placing into and out of operative relation with the key-bars, some of which are shown in cross-section.

Fig. 2 is a corresponding view of a combination bar of another set, the key-bars not being shown.

Fig. 3 is a corresponding view of the universal bar.

Referring to the drawings, in a keyboard mechanism for the five-unit teleprinter code there are provided two sets of combination bars, five in each set. One of these sets of combination bars, to which the combination bar 1, Fig. 1 belongs, is normally supported in position immediately below the key levers of the keyboard. Only those key levers 2 that carry keys having two symbols thereon are shown in the drawing. Another set of five combination bars, to which the combination bar 3, Fig. 2 belongs, is normally supported in a lower position so that these combination bars are not actuated by any of the keys. A universal bar 4, Fig. 3, is supported so as normally to be actuated by any character key lever the key of which is depressed.

The combination bars, such as 1 and 3, and the universal bar 4, are mounted in racks, of which one only 5, is shown to space them apart and keep them upright. They rest on rollers 6 supported on a base plate 7. The rollers 6 are rotatably mounted on pins 8 fixed to a bar 9, Fig. 1. The combination bars of one set, such as bar 1, are formed with projections 10, underneath, these projections being formed with a flat surface of sufficient extent to allow each bar being moved to right or left by a key lever, the projection 10 being bounded on the left in Fig. 1 by a ramp 11. It should be noted however, that bar 1 is shown in its extreme left hand position so that in this

position the right hand key lever 2 will leave the bar 1 unmoved. Should the bar 1 be moved to the right by actuation of a key lever 2 such as the left hand key lever of the three levers shown in Fig. 1 then the subsequent actuation of the right hand lever 2 will move it back to the left into the position shown. The combination bars of the other set, such as bar 3, Fig. 2 are formed with similar projections 12 underneath, each projection 12 being bounded on the right in the drawing by a ramp 13. The combination bars of the last mentioned set rest with the ramps 13 adjacent to the rollers 6 so that the bars are below a level at which they can be operated by the key levers.

The bar 9 is linked by a bell crank lever 14 to the shift key lever 15. When the shift key lever is depressed the bell crank lever 14 is rotated clockwise and moves the link 9 to the left. The rollers 6 move below the ramps 11 of the projections 10 on the combination bars 1 so that these bars drop to a level too low to be operated by the key levers 2. At the same time the ramps 13 on projections 12 rise up, the rollers 6 thus raising the combination bars such as 3 to a level at which they can be operated by key levers 2.

The universal bar 4 is supported on the rollers 6 by projections 16 under the bar, these projections 16 having a flat surface underneath of sufficient extent for the bar 4 to remain in operative relation to the key levers 2 in either of the two positions of link 9.

The combination bars control a transmitter by means of signal control levers 17, Fig. 1, 18 Fig. 2 and 19 Fig. 3. Assuming that combination bars 1 and 3 are corresponding bars of the two sets, signal control levers 17 and 18 are similarly linked to the same member of the transmitter or perforator. The signal control levers 17, 18 and 19 are linked with the bars 1, 3 and 4 respectively by means of notches 20 in the latter so that when combination bar 1 is lowered by movement of the link 9 the end of control lever 17 no longer engages in the notch 20 in the combination bar and the latter is no longer operatively connected with signal control lever 17. Similarly when combination bar 3 is raised by movement of link 9 the notch 20 in bar 3 engages the end of control lever 18 so that it is operatively connected therewith. The notches 20 are formed with bevel edges so that the end of the corresponding control lever 17 or 18 will always be engaged therein when the combination bar is raised.

The sideways movement of the link 9 is effected against the tension of a spring (not shown) so that when the shift key lever 15 is released by this spring to its original position and again raises the set of combination bars to which bar 1 belongs into operative relation with the key levers and lowers the set of combination bars to which bar 2 belongs out of operative relation with the key levers.

The movement of the combination bars by the link 9 is limited by means of stop rollers 21 which provide reaction points to enable the sloping edges 11 or 13 of projection 10 or 12 to lift the bar 1 or 3.

Corresponding bars 1 and 3 of the two sets of combination bars are preferably arranged in juxtaposition the bars of the two sets being arranged alternately to facilitate the operation of the same member of the transmitter by either of the signal control levers 17, 18.

While the principles of the invention have been described above in connection with specific embodiments and particular modifications thereto, it is to be clearly understood that this description is made only by way of example and not as a limitation on the scope of the invention.

What is claimed is:

1. Keyboard mechanism for telegraph apparatus, comprising a set of character key levers, a first set of combination members positioned in operative relation to said character key levers, a second set of combination members positioned out of operative relation to said character key levers, a shift key lever and means, operative upon actuation of said shift key lever for placing the second set of combination members in and removing the first set of combination members out of operative relation to said character key levers.
2. Keyboard mechanism as claimed in claim 1 in which said combination members are combination bars formed with projections resting upon rollers attached to a link a shift key lever for moving said link, said projections being so formed that movement of the link in one direction raises one set of combination bars and lowers the other.
3. Keyboard mechanism as claimed in claim 1, further comprising signal control means, and utilization means, said signal control means adapted to link said combination members to said utilization means when said combination members are moved into operative relation with said key levers.
4. Keyboard mechanism as claimed in claim 3, wherein said utilization means comprises a telegraph transmitter.
5. Keyboard mechanism as claimed in claim 3, wherein said utilization means comprises a message tape perforator.
